STORAGE HANGER FOR ARTICLES OF CLOTHING OR THE LIKE

Lynne Forrester, 162 W. 54th St., New York, N.Y.

Filed Aug. 1, 1960, Ser. No. 61,589

Term of patent 14 years

(Cl. D80—8)

FIG. 1

FIG. 3

FIG. 1 is a perspective view of a storage hanger for articles of clothing or the like embodying my new design;

FIG. 2 is a side elevational view thereof;

FIG. 3 is an enlarged top plan view thereof;

FIG. 4 is a perspective view of a modified form thereof;

FIG. 5 is a side elevational view of the modified form thereof; and

FIG. 6 is an enlarged top plan view of the modified form thereof.

I claim:

The design for a storage hanger for articles of clothing or the like, as shown and described.
